Inventor:

Gottlieb H. Hutttenlocher.

By Thomas G. Orwig, Attorney.

UNITED STATES PATENT OFFICE.

GOTTLIEB H. HUTTENLOCHER, OF DES MOINES, IOWA.

KEY-FASTENER.

SPECIFICATION forming part of Letters Patent No. 429,239, dated June 3, 1890.

Application filed September 13, 1889. Serial No. 323,883. (No model.)

To all whom it may concern:

Be it known that I, GOTTLIEB H. HUTTENLOCHER, a citizen of the United States of America, and a resident of Des Moines, in 5 the county of Polk and State of Iowa, have invented a Device for Fastening a Key in a Door-Lock, of which the following is a specification.

Heretofore an escutcheon-plate has had an 10 integral lateral extension, and the parallel side portions of said extension bent toward the center to produce bearings on the outside of the escutcheon, in which bearings was fitted a slide that had a bifurcated end adapted 15 to engage the stem of a key in the door-lock in such a manner that a person on the outside of the door cannot turn the key or remove it by means of any key or instrument introduced into the key-hole from the out- 20 side, as required to unlock the door from the outside.

My invention consists in the construction and combination of a slide with a key-hole escutcheon and lock on a door, as hereinafter 25 set forth, pointed out in my claim, and illustrated in the accompanying drawings, in which—

Figure 1 shows the under side of a key-hole plate or escutcheon that has a lateral extension 30 to which a slide is attached. Fig. 2 is a sectional view through the line $x-x$ of Fig. 1. Fig. 3 is a face view, and Fig. 4 an edge view, of a piece of a door to which my complete device is applied as required for practical use.

35 A represents an escutcheon that may vary in shape and size, as desired.

B is a lateral extension of the escutcheon-plate, preferably made integral therewith. Dotted lines in Fig. 1 indicate that it may be 40 extended from the opposite edge, as required for a left-hand door.

c is a right-angled projection on the under side of the part B.

d is a sliding plate on the top of the extension B. It has a slot *f* in its front end adapting it to slip off and on the flat stem of a door-key of common form. It also has an outward projection or knob *g*, formed on or fixed thereto, that is adapted to be engaged by a person's fingers, as required to move the slide 45 on and off the stem of a key when the door is locked and the key is left in the key-hole engaged with the bolt of the lock.

h is a slot in the plate B, and *i* is a block fitted in the slot and fixed to the plate *d*, so 50 that it will overlap the edges of the slot, as required to retain the plate *d* flat upon the plates A B and to slide with the plate *d*.

m is a coiled spring fixed to the block *i* and the projection *c*, so that it will in its normal 55 condition press the slide *d* across the key-hole to engage and hold the key fast in the lock in the position shown in Fig. 4.

The part B may be formed separate, as indicated by dotted lines in Fig. 3, and attached to a door at the side of a fixed escutcheon by means of screws.

The spring may be dispensed with and the slide moved in opposite directions by pressure upon the knob *g*, as required to fasten 70 and unfasten a key in the key-hole.

I claim as my invention—

The plate A, the extension B, provided with a projection *c* and slot *h*, the slide *d*, having a slot *f*, a projection *g*, and fixed block 75 *i*, and a spring *m*, constructed and combined to operate in the manner set forth, for the purposes stated.

GOTTLIEB H. HUTTENLOCHER.
